[57] CLAIM

The ornamental design for a boxing glove, as shown and described.

DESCRIPTION

FIG. 1 is a top plan view of a right hand boxing glove showing my new design, the left hand boxing glove being a mirror image thereof;

FIG. 2 is a front elevational view thereof;

FIG. 3 is a right side elevational view thereof;

FIG. 4 is a rear elevational view thereof;

FIG. 5 is a left side elevational view thereof; and

FIG. 6 is a bottom plan view thereof.

The broken lines continuing from the tie laces in FIGS. 2-5 indicate indeterminate length.
